UNITED STATES PATENT OFFICE.

JOHN A. NEWELL, OF COCHRAN, INDIANA.

RECLINING-CHAIR.

SPECIFICATION forming part of Letters Patent No. 352,773, dated November 16, 1886.

Application filed January 8, 1886. Serial No. 188,023. (No model.)

To all whom it may concern:

Be it known that I, JOHN A. NEWELL, of Cochran, Dearborn county, Indiana, have invented a new and useful Improvement in Reclining-Chairs, of which the following is a specification.

My invention relates to improvements in those adjustable chairs which are made capable of conversion from a sitting to a reclining, to a recumbent, or other form at will.

In the accompanying drawings, Figure 1 is a side elevation representing an articulated rocking-chair embodying my invention, portions in this and succeeding figures being removed or broken away to display the working parts. Fig. 2 is a top view of the forward portion of the chair, the foot-rest being shown extended. Fig. 3 is a rear view of the winding or stretching device of the hammock. Fig. 4 is a section of the catch of the arm-slide. Fig. 5 is a side elevation of the adjusting mechanism of the foot-rest. Fig. 6 is a vertical section of the chair in condition of a rocking couch. Fig. 7 is a side elevation of my chair in condition of a cot or hammock bed. Figs. 8 and 9 are respectively a vertical section and a side elevation of a portion of one of the chair rockers with my removable foot attached thereto.

The base or lowest member of my chair consists, preferably, of a rocking frame, A, from whose front portion rise two rigidly-attached posts, B, that are firmly joined at their upper parts by a stretcher or cross-piece, C. Connected by pivots D to the rocking frame a little in rear of its mid-length are the two sides of my chair-back E, which sides are at their upper ends firmly joined together by a stretcher, F. Connected by pivots D' to the upper ends of posts B are standards G, whose upper ends are in turn similarly articulated by pivots D" to the chair-arms H. Spring-catches I on the rear ends are capable of engagement in any of the series of holes e in the sides of the chair-back E. These holes e are in the bottom of a groove, e', in said sides, which groove holds a slide, J, which is traversed by the pin i of the spring-catch I, and which has a stud, j, that occupies an eye, h, in the rear end of arm H.

To support the occupant I provide a pail-lasse or hammock, K, of stout canvas or other

strong and flexible material. The lower or front end of said hammock has a loop or hem, k, which is engaged around a removable rod, L, that occupies orifices b in the posts B. The upper or rear end of said hammock has loops k', which are engaged on studs m of a windlass, M, which is journaled in the upper part of the back E, and has at one or both ends a handle, m', for winding it up. N is a spring-catch, 60 whose pin n, by engaging in holes m", in a collar of said windlass, retains it to any desired adjustment, so as to hold the hammock to either a stretched or a slack condition, as may be required. This construction permits ready 65 substitution of a clean or new hammock for a worn or soiled one, or the application of hammocks of different material—such, for example, as are suitable for summer and winter use, respectively, or for use by invalids.

The standards G and the chair-arms H are retained in any regular position to which they may be adjusted by pin o of spring-catch O upon the arm engaging in one or other notch p of segment-rack P upon the standard G. 75 The hinges Q serve to secure to the posts B a leg-rest, T, to which is secured by hinges Q" a foot-rest, U. The leg-rest T is capable of being held at any desired angular elevation by brace V, whose lower end may engage in any 80 notch of a rack, W, and may be released therefrom by bar X, secured by pivot x to the end of a bent lever, Y, within convenient reach of the occupant. The foot-rest U may be supported at any desired angle by means of chains 85 Z, which extend from the upper part of the leg-rest to hooks u, so as to make said foot-rest available for use in the sitting conditions of the chair. Said foot-rest is also capable of being made available for use in the recumbent or semi-reclining position by releasing the chains Z and suffering the said foot-rest to rest upon the shoulders t of the leg-rest T, as seen in Fig. 2.

Secured by hinges Q to post B is a seat or 95 cushion, R, which, when folded upward and backward, as shown in Fig. 1, serves as a seat, and when unfolded, as shown in Figs. 6 and 7, rests upon the foot-rest, (which is raised to support it at any desired angle,) and does duty 100 as an extension of the hammock, and may be utilized to support the occupant's feet, as in

the recumbent form shown in Fig. 6, or to support the occupant's head, as shown in the reclining form represented in Fig. 7.

Secured by hinges Q' to seat or extension R 5 is an additional extension, S, having a padding, s, on one side of it. This extension may be unfolded, as in Fig. 6, so as to serve as a foot-rest for the occupant in the recumbent position, or may be folded over upon the extension R, so as to present its padded surface s uppermost, for a head-rest for the occupant when in a reclining position. (See Fig. 7.)

In the reclining form shown in Fig. 7 the chair or cot is supported in front on its rockers A and at back on the extremities of its back side pieces, E, so that in this condition the article is no longer a rocking one, but stands firmly on the four points of support afforded by the rocking frame and the back. 15 The chair may also be prevented from rocking in any one of its other positions—such as those shown in Figs. 1 and 7, by attaching to one or both ends of each rocker a removable foot, 1, whose yoke 2 embraces the rocker and 20 has tapped into it a set-screw, 3, which bears against a follower, 4, between which and the yoke the rocker is clamped, together with interposed india-rubber pieces 5, by means of said set-screw. The india-rubber pieces enable 25 tighter clamping and prevent injury to the rocker-surface.

I disclaim a seat which rests upon the side pieces of a hammock-chair and is held by lugs, as such is not new.

35 I claim as new and of my invention—

1. In a reclining-chair, the combination, with the rocking base-frame A B C, of the back-frame E F, pivoted to the rockers A of said base-frame, and having in its sides grooves e' 40 and rows of holes e, arms H, having at their outer ends hinged and angularly-adjustable connection with the posts B, and at the other ends slides J, riding in the grooves e', and pins i, which pass through slides J and engage said 45 holes e, substantially as set forth.

2. In a reclining-chair, the combination, with the rocking base-frame A B C, of the back-frame E F, pivoted to the rockers A of said base-frame, standards G, pivoted to the upper extremities of posts B, and having segment-racks P, arms H, pivoted at their front ends to said standards, spring-catches O on said arms engaging with segment-racks P, and adjustable connections between the rear ends of arms H and the back E F, substantially as 55 set forth.

3. In an adjustable chair, the combination, with the removable rod L, that occupies holes in the posts B, and with a windlass, M, in the chair-back E, having the handle m', spring- 60 catch N, and studs m, of the removable paillasse or hammock K, having at one end a loop or hem, k, and at the other end loops k', which engage said studs m, substantially as set forth.

4. In combination with a chair having a 65 stretcher or hammock, a seat or cushion hinged to the front part of the chair between the front legs, and so adapted to rest at its free extremity directly upon said stretcher, whereby the latter is held taut, substantially as set 70 forth.

5. In combination with a chair having a stretcher or hammock, K, a seat or cushion, R, hinged to the front part of the chair, and an additional extension, S, hinged to the seat 75 or cushion R, and having the pad s, substantially as and for the purposes set forth.

6. In combination with a rocking-chair, the removable foot 1, having rocker-embracing yoke 2, with clamping set-screw 3, follower 4, 80 and the india-rubber pieces 5, interposed between the rocker and the clamping-surfaces, substantially as and for the purposes set forth.

In testimony of which invention I hereunto set my hand.

JOHN A. NEWELL.
